179,431

OUTDOOR STOVE

Milton H. Sellhorn, Northbrook, and Larry S. Henry and George F. Henry, Morton Grove, Ill., assignors to George Henry Company, Morton Grove, Ill., a corporation of Illinois

Application December 7, 1955, Serial No. 39,186

Term of patent 14 years

(Cl. D81—10)

Fig. 1

Fig. 2

Des. 179,431

PAGE 2

Fig. 3

Figure 1 is a side elevation of an outdoor stove embodying our new design;

Figure 2 is an end view of said stove;

Figure 3 is a perspective view thereof; and

Figure 4 is a perspective view thereof with the hood in open position.

We claim:

The ornamental design for an outdoor stove, as shown.

References Cited in the file of this patent

UNITED STATES PATENTS

D. 163,090	Campbell	-----	May 1, 1951
D. 163,111	Gibbon	-----	May 1, 1951
D. 164,881	Roth	-----	Oct. 16, 1951

OTHER REFERENCES

The Decorative Furnisher, volumes 71-72, July 1937, page 18, table No. 5 in center.